HOLDER FOR USE IN REPOINTING
TWIST DRILLS

David Crowther, Minneapolis, Minn.

Application October 30, 1943, Serial No. 508,432

4 Claims. (Cl. 51—219)

My invention relates to holders for use in re-pointing twist drills. It relates more particularly to a device to be held in the hand of the operator with the drill which is to be re-pointed clamped in the device in order to grind the cutting end of the drill at the most desirable and efficient angles and without the device having any attachment whatever to a grinding machine. An object therefore is to provide a device of this character which is simple and inexpensive to manufacture and at the same time is efficient and convenient for holding the drill so that it may be properly brought into engagement with a grinding wheel for accurately sharpening a dull drill.

In the metal drilling art, a twist drill has a body portion provided with a "point," the latter being the entire cutting end. Two deeply cut spiral grooves known as flutes extend along the sides of the body member, these grooves being diametrically opposite each other. A sharp tip at the extreme end of the drill is formed by the intersection of the flutes and the cutting edges or lips, and this tip must be kept in the exact center of the axis of the drill. The heel is the portion of the "point" back of the cutting lips. An efficient cutting edge for the lips would not be provided unless they are sharp. So in order to give this cutting edge, the surface of the "point" must be ground exactly back of the lips, this being known as lip clearance. This clearance allows the lips to enter the metal which is being drilled and the effectiveness of the drill depends largely on the grinding of the lip clearance at the proper angle which is 12° at the periphery of the drill. Furthermore, the most desirable angle which is given to the cutting lips is considered to be 29½° with relation to the axis. With the foregoing explanation in mind, it will be understood that the object of my invention is to provide a device by means of which the angles just referred to may be readily and accurately ground in order to properly re-point the drill.

The novel features which I believe characteristic of my invention are set forth with particularity in the appended claims. The invention, however, both as to its organization and method of operation, together with additional objects and advantages thereof, will be best understood from the following description of a specific embodiment thereof when it is read in connection with the accompanying drawing in which,

Fig. 1 is a sectional view showing the point of a drill in proximity to a grinding wheel.

Fig. 2 is a view of the device taken on the line x—x Fig. 1.

Fig. 3 is a side elevational view of a slight modification.

Fig. 4 is a cross sectional view of the block used. Referring to the construction shown in the accompanying drawing in order to illustrate the principles involved in this invention, the numeral 1 designates a cone-shaped member of wear resistant material such as carborundum having an axial bolt 2 secured thereto and projecting from the larger end of the member 1. This projecting end portion is screw threaded. A block 3 is provided with one or more longitudinal V shaped grooves 4, 4' and with a hole 5 for receiving the bolt 2. A hollowed out clamping nut 6 containing a coiled spring 7 is threaded on the screw threaded portion of the bolt 2 in order that a drill D may be firmly held in the groove between the block 3 and the larger end of the member 1. As shown, the hole 5 in the block 3 is so located that the forward end of this block projects slightly beyond the periphery of the larger end of the member 1. A stop member 8 is preferably provided, this member containing a set screw 9 which when turned down clamps the member 8 to the body portion of the drill. This stop assists in keeping the drill in the same longitudinal position in the groove 4 when the drill is turned exactly half way around therein in order to grind the opposite side of the point exactly the same as the side already ground.

The operation and advantages of my invention will be readily understood in connection with the foregoing description and the accompanying drawing. In order to re-point a drill when it becomes dull, the drill is placed in the groove at the right hand portion of the block 3 with the "point" of the drill extending beyond the rear end of the block the proper amount to be ground away as determined by the position of the stop member 8. The device is held in the hand of the operator and brought into proximity with the surface of a grinding wheel G until the "point" of the drill is ground down as much as the cone member 1 will permit when it comes into contact with the grinder. The device holding the drill is given a slight back and forth rotative movement with the "point" in engagement with the grinding wheel and the heel is ground away to provide the proper angle for lip clearance. When inserting the drill in the groove, it must be so positioned therein that the tips of the two cutting lips are equally distant from the top of the larger end of the cone member 1.

When the two angles just referred to have been ground on one side of the "point," the drill is

turned half way around in the groove, the stop member 8 when provided assisting to make sure that the drill is properly positioned in the groove. The grinding process just described is then repeated so that the other side of the "point" is ground exactly the same as the first side.

In regard to obtaining the proper angle for the lip clearance of the heels back of the lips, it should be recalled that if two parallel straight lines are drawn across a circle not going through the center thereof, the angles which the lines make at the periphery of the circle will vary according to the distance which they are from the center of the circle. This principle is made use of in obtaining the desired angle for the lip clearance. The two lines may be considered as representing the two opposite sides of the drill in the groove and the circle is the periphery of the larger end of the cone-shaped member 1. Therefore by placing the V groove the proper distance from the center of said larger end, the desired angle for lip clearance will be obtained. It will be understood as a matter of course that the two lines may be varied in accordance with the size of the drill and that different blocks may be provided in accordance with thickness of the drills. Fig. 2 shows a second groove 4' which is diagonally opposite the groove 4 so as to be on the other side of the axis of the member 1 and it is at a slightly different distance therefrom. In case the cone member 1 in time should wear down slightly, this groove may then be used in which to hold the drill. The groove 4' also provides for receiving a drill of different size.

I have already indicated that more than one groove may be made in the block 3 and that the groove which is used must be on the right hand side. It is therefore obvious that if the block be made square in cross section and provided with two holes at right angles to each other, then a groove may be provided in each of the four faces.

Figs. 3 and 4 show a block 10 square in cross section and provided with a groove in each of its four faces, these grooves being designated 11, 12, 13, and 14 in Fig. 4. The block 10 is provided with two holes 5 and 5' at right angles to each other. Fig. 3 shows the position of the lips of the drill with respect to the holder and the grinding wheel.

I claim:

1. A holder for use in re-pointing twist drills comprising a cone-shaped member of wear resistant material, a block containing at least one longitudinal groove, and means for clamping the drill in the groove between the block and the larger end of the cone-shaped member in such position that when the drill is placed adjacent to a grinding device the cutting lips of the drill may be ground down to the angle of inclination of the cone-shaped member and the distance of said

groove from the axis of the cone-shaped member being such that the heel portions of the drill may be ground down at an angle determined by said distance.

5. 2. A holder for use in re-pointing twist drills comprising a cone-shaped member of wear resistant material, an axial bolt secured to said member and projecting from the larger end thereof with the projecting portion screw threaded, a block containing at least one longitudinal groove and having a hole into which said bolt is inserted, and a clamping nut threaded upon said projecting portion for holding the drill in the groove between the block and the larger end of the cone-shaped member in such position that when the drill is placed adjacent to a grinding device the cutting lips of the drill may be ground down to the angle of inclination of the cone-shaped member and the distance of said groove from the axis of the cone-shaped member being such that the heel portions of the drill may be ground down at an angle determined by said distance.

3. A holder for use in re-pointing twist drills comprising a cone-shaped member of wear resistant material, a block containing two longitudinal grooves on opposite faces thereof and at different distances from the axis of said cone-shaped member, and means for clamping the drill in either one of said grooves between the block and the larger end of the cone-shaped member in such position that when the drill is placed adjacent to a grinding device the cutting lips of the drill may be ground down to the angle of inclination of the cone-shaped member and the distance of said grooves from the axis of the cone-shaped member being such that the heel portions of the drill may be ground down at an angle determined by said distance.

4. A holder for use in re-pointing twist drills comprising a cone-shaped member of wear resistant material, a block containing at least one longitudinal groove, means for clamping the drill in the groove between the block and the larger end of the cone-shaped member, and a stop member adapted to be clamped on the body portion of the drill in such position that the engagement of the stop member with the front end of the block will determine the desired projection of the

50 "point" of the drill beyond the cone-shaped member in such position that when the drill is placed adjacent to a grinding device the cutting lips of the drill may be ground down to the angle of inclination of the cone-shaped member and the distance of said groove from the axis of the cone-shaped member being such that the heel portions of the drill may be ground down at an angle determined by said distance.
